Primary Examiner—Bernard Ansher*Assistant Examiner*—M. Siegel[57] **CLAIM**

The ornamental design for a cartridge pressurization tool, as shown and described.

DESCRIPTION

FIG. 1 is a perspective view of the cartridge pressurization tool showing our new design;

FIG. 2 is a top view thereof;

FIG. 3 is a left side elevational view thereof, the undisclosed opposite side being identical;

FIG. 4 is a rear elevational view thereof;

FIG. 5 is a bottom view thereof; and,

FIG. 6 is a reduced front elevational view thereof.
